JOSEPH SACHS, OF HARTFORD, CONNECTICUT.

ELECTRIC SWITCH.

1,258,256.

Patented Mar. 5, 1918.

Application filed March 31, 1915. Serial No. 18,226.

To all whom it may concern:

Be it known that I, JOSEPH SACHS, a citizen of the United States, residing at Hartford, in the county of Hartford and State of Connecticut, have invented certain new and useful Improvements in Electric Switches, of which the following is a specification.

This invention relates to electric switches. 10 While the invention is susceptible of general use, it is of especial utility when incorporated in a snap switch. Among the objects of the invention are the provision of an article of this character which is exceedingly 15 simple in construction, which consists of the minimum number of parts, which can be inexpensively made, the parts readily and easily assembled, the switch being susceptible of easy action and positive and certain 20 in its operation. The device possesses other features of novelty and advantage which with the foregoing will be stated at length in the following description wherein I will set forth that one of the several forms 25 of embodiment of the invention which I have selected for illustration in the drawings accompanying and forming part of the present specification. As will be understood, I do not restrict myself to this particular disclosure; I may depart therefrom 30 in several respects within the scope of the invention defined by the claims following said description.

Referring to said drawings:

35 Figure 1 is a side elevation,

Figs. 2 and 3 are vertical sections at right angles to each other, and

Fig. 4 is a top plan view with the upper section of the casing removed, of a switch 40 involving my invention.

Fig. 5 is a detail view in perspective of a switching member and contact pieces carried thereby.

Fig. 6 is a like view of an actuator.

45 Like characters refer to like parts throughout the several views.

The switch comprises in its make up, a suitable supporting body such as that denoted by 2, said body being of some insulating material such as porcelain and preferably being incased, the casing 3 being shown for this purpose. Said casing is composed of two sections connected by a screw threaded joint, the lower or main section 55 being connected in some suitable manner as by the screw 4 with the insulating body 2.

As shown said insulating body has a chamber 5 hereinafter more particularly described, the screw 4 projecting downward through a hole or opening 6 extending from the flat bottom of said chamber 5, the head of the screw being received in a countersink at the upper end of said hole and the threaded portions thereof fitting a threaded opening in the lower or main section of the casing 3. Between the upper or cap section of the casing and the insulating body is interposed insulation as 7 which overlies the base of the bushing 8 extending into the projecting neck 9 of the upper section of said casing. Through this bushing the wires of a cord may pass to be connected electrically to companion wire connecting and contact members as 10, the bodies of which are fastened as by screws or otherwise to the upper flat side of the insulating body 2. The wires are fitted around screws as 11, the heads of which clamp said wires against the bodies of the wire connecting and contact members 10, said screws being 80 threaded into said bodies. The wire connecting and contact members are provided with contact portions 12 projecting into the chamber 5. As will be obvious in this particular embodiment of the invention, the device is adapted to act as a pendant switch; being also as will hereinafter appear of snap type. The chamber 5 which receives the switching member hereinafter described and the snap means for operating the same between the on and the off positions, comprises a lower portion 13 and an upper portion 14, the side walls of the lower portion as represented being in parallelism with each other while the end walls are upon a downward inward taper or slant. The upper portion 14 of the chamber is rectangular, the two portions being concentric. The contact portions 12 are disposed in the rectangular portion 14 near one end thereof. 90

The switching member is denoted in a general way by 15, it being approximately of yoke or inverted U-form, the side branches of the switching member having outwardly projecting duplicate pivots or studs 16 105 which may consist of rivets driven through openings or perforations near the free ends of said branches from the outside thereof and headed on the inside. Externally of the switching member are two contact portions 17 of duplicate construction, the studs 16 in addition to serving as pivots acting to 110

hold the contact portions 17 in place, the contact portions near their bases or butts being perforated and the studs or pivots 16 being driven through these perforations so 5 as to hold the respective contact portions 17 in alinement with the adjacent branches or sides of the yoke-like switching member 15. The two contact portions 17 as shown are resilient and although they abut against the 10 outer faces of the branches of the switching member 15, their upper portions are free thereof so as to insure the requisite resiliency or freedom of said contact portion 17 which as illustrated are practically coextensive with the sides or branches of the yoke-like switching member 15. The lower portion 13 of the chamber of the body 2 has notches as 18 in its side walls diametrically opposite each other, the lower closed end of 15 said V-shaped notches being practically in alinement with the bottom of the chamber. In the sides of the chamber 5 and shown as formed approximately centrally of the notches 18 are slots 19 disposed opposite to 20 each other, the lower ends of these slots being closed and their upper ends being open and opening into the ledge or shoulder formed at the junction of the two portions 13 and 14 of the chamber 5. In assembling 25 the parts the two pivots or studs 15 are entered into the upper ends of the mating slots 19, the switching member being lower until the studs strike the lower closed rounded ends of the slots, which ends present proper 30 bearings for the two studs or pivots. From this as will be inferred, the switching member 15 has a rocking or swinging motion. The side walls of the notches 18 limit the motion of the switching member, said 35 switching member being adapted to engage opposite side walls of the notches when in the off and on positions.

The means shown for effecting the oscillation alternately in opposite directions of 40 the switching member 15 may as shown include an actuator as 20 which as shown extends through the lower portion of the chamber 5 and also through perforations 21 opening into said chamber from the exterior 45 of the body 2. This actuator 20 also extends through properly positioned holes or perforations in the casing 3, its ends being always exteriorly accessible. As represented the actuator consists of an approximately one- 50 piece cylindrical rod which may be wholly of insulating material, and provided approximately centrally thereof, with the reduced portion 22 having the perforation 23 which may as shown receive a hook at the 55 lower end of the spring, the other end of which spring is hooked over the notched part 25 of the transverse portion of the switching member 15.

It will be noted that the switching member 15 and the actuator 20 are each directly

supported by the insulating body 2; that is to say, I dispense with an individual support for sustaining this switching member and actuator, the consequence being that the switch as already observed consists of a few 50 number of parts. As a matter of fact there is merely a body, a switching member and spring and actuator with the necessary contacts and securing means. When I say that the switching member is directly supported 55 by the body, I do not mean to imply that I may not interpose between the switching member and the body wear resisting means, such for example as metal bushings which receive the pivots 16. I mean to imply that 60 I dispense with an individual support for the switching mechanism and utilize the body itself as such a support.

It becomes a simple matter to assemble 65 the parts. The lower section of the casing 3 can first be fitted to the body 2 after which the actuator 20 can be inserted in place, following which the switching member 15 can be positioned and finally the spring 24 can be connected to the switching 70 member and actuator respectively. The wire connection and contact members if not already mounted can be put in place and the upper section of the casing 3 can be applied. 75

It will be noted that the actuator 20 operates an over the center spring as 24 and that the latter in turn causes the on and off movements of the switching member 15. The dead center line of this spring extends 80 through the center of movement of the switching member 15 and the center of connection between the spring 24 and the switching member. In Fig. 2 the switching member is shown by full lines as off, the 85 actuator-connected end of the spring being to the right of the dead center line. To move the switching member to on the actuator 20 will be thrust to the left and the moment the dead center line is crossed the 90 spring will snap the switching member to on as shown by the dotted lines in said view, so that the contact portion 17 of the switching member can engage the contacts of the 95 wire connecting and contact members 10. 100

I have described the fact that means are provided for arresting the switching member 15 when in its respective positions. Means are also provided for performing a 110 like function with respect to the actuator 20 and as shown this is accomplished by the spring 24, which is connected to said actuator 20 alternately striking the tapered ends of the lower portion 13 of the chamber. 115

What I claim is:

1. A switch comprising an insulating body having a chamber, an oscillatory switching member in said chamber provided with pivot means, the body directly supporting 120

the pivot means, an endwise movable actuator extending entirely through and projecting at its ends from said body, and means operated by the actuator for causing snap movement of the switching member on each movement of the actuator.

2. A switch comprising an insulating body having a chamber, an oscillatory switching member in said chamber, the body having a part thereof for directly sustaining the switching member, an endwise movable actuator extending entirely through and projecting at its ends from said body, and means operated by the actuator for causing the snap movement of the switching member on each movement of the actuator.

3. A switch comprising an insulating body, a switching member, the body having a part thereof for directly sustaining the switching member for movement, and means for effecting as desired the action of the switching member.

4. A switch comprising an insulating body having a chamber, the opposite walls of which are slotted, the slots having bearing portions and the upper ends being open, an oscillatory U-shaped switching member having a cross bar and provided with pivots supported by the bearing portions of the slots, an actuator extending entirely through the supporting body and movable back and forth, and means connected with the cross-bar of the switching member and operated by the actuator, for causing a snap movement of the switching member on each operation of the actuator.

5. A switch comprising an insulating body having a chamber, an oscillatory switching member directly supported by the side walls of the chamber, said walls having integral means for arresting the switching member when in the on and the off positions, actuating means, and means operated by the actuating means for moving the switching member to on and off positions on successive operations of the actuating means.

6. A switch comprising an insulating body having a chamber, the side walls of which have V-notches, and also having bearing openings, said notches and openings being formed directly in said side walls, an oscillatory switching member having pivots in said bearing openings, the side walls of the notches arresting the switching member when in the on and the off positions thereof, actuating means, and means operated by the actuating means for causing on and off movements of the switching member on successive operations of the actuating means.

60 7. A switch comprising an insulating body having a chamber, the side walls of which have V-notches, and also have slots closed at their lower ends and open at their upper ends, said notches and slots being formed directly in said side walls, an oscillatory

switching member provided with pivots having bearings against the closed ends of the slots, the side walls of the V-notches arresting the switching member when in the on and off positions thereof, actuating means, and means operated by the actuating means for causing on and off movements of the switching member on successive operations of the actuating means.

8. A switch comprising an insulating body having a chamber, an oscillatory switching member in said chamber, said switching member having contacts on its outer sides, opposite walls of the chamber having bearings formed directly therein, for the switching member and said walls also having means for arresting the switching member when in the on and off positions thereof, actuating means, and means operated by the actuating means, for causing on and off movements of the switching member on successive operations of the actuating means.

9. A switch comprising an insulating body having a chamber, an oscillatory switching member in said chamber, said switching member having outer sides provided with resilient contacts, an actuator supported for back and forth movement by the body, a spring connected with the actuator and also with the switching member at a point removed from the center of movement of the switching member, the actuator connected end of the spring being normally at one side of a dead center line intersecting the center of connection between the spring and the switching member and the center of motion of the switching member, the actuator on each of its movements being adapted to move the actuator connected end of the spring across said dead center line and the spring being adapted alternately to engage opposite walls of the chamber to limit the movement of the actuator.

10. A switch comprising an insulating body having a chamber, an oscillatory switching member in said chamber, an actuator supported for back and forth movement by the body, a spring connected with the actuator and also with the switching member at a point removed from the center of movement of the switching member, the actuator connected end of the spring being normally at one side of a dead center line intersecting the center of connection between the spring and the switching member and the center of motion of the switching member, the actuator on each of its movements being adapted to move the actuator connected end of the spring across said dead center line and the spring being adapted alternately to engage opposite walls of the chamber to limit the movement of the actuator, the other walls of said chamber having means for limiting the movement of the switching member.

11. A switch comprising an insulating body having a chamber, opposite walls of which have bearing openings, a switching member of inverted yoke form, having a cross bar, the sides of which are provided resilient contacts and also with pivots fitted in said bearing openings, an actuator mounted for back and forth movement and supported by the body, the actuator extending between the sides of the switching member, and means operated by the actuator and connected with the crossbar of the switching member, for moving the switching member to on and off positions on successive operations of the actuator.
12. A switch comprising an insulating body having a chamber, an inverted yoke like switching member in said chamber, the sides of which are provided with outwardly extending pivots, opposite walls of the chamber having bearing openings to receive said pivots, resilient contacts fitted to said sides and held thereto by said pivots, an actuator extending through the switching member and movable back and forth, and means operated by the actuator for moving the switching member to on and off positions on successive movements of the actuator.
13. A switch comprising an insulating body, an oscillatory switching member supported directly by said body, actuating means supported directly by said body for back and forth movement, spring means connected with the actuating means and also with the switching member, the spring means at the point where it is connected with the actuating means being normally at one side of a dead center line intersecting the center of connection between said spring means and the switching member and the center of motion of the switching member, the actuating means on each of its movements being adapted to move that end of the spring means which is connected with the actuating means across said dead center line, and means for arresting the movement of the switching member and the actuating means when in predetermined positions.
14. A switch comprising an insulating body having a chamber, opposite walls of which have bearing openings, a switching member, the sides of which are provided with pivots in said bearing openings and also with exterior contacts, actuating means mounted for back and forth movement and supported by the body, and means operated by the actuating means for moving the switching member to on and off positions on successive operations of the actuating means.
15. A switch comprising an insulating body having a chamber, an inverted yoke like switching member in said chamber, said switching member comprising sides and a cross bar connecting said sides, the sides of the switching member having pivots and opposite walls of the chamber having bearing openings directly therein, to receive said pivots, an actuator extending through the switching member and movable back and forth, and means operated by the actuator and connected with the crossbar of the switching member, for moving the switching member to on and off positions on successive movements of the actuator.
16. A switch comprising an insulating body provided with relatively fixed contacts and having a chamber, an inverted yoke like switching member in said chamber, the surface of the chamber having means for directly supporting said switching member for swinging movement, the branches of said switching member being provided with exterior resilient contacts and said switching member being movable to on and off positions and having contacts which engage with the relatively fixed contacts when said switching member is in the on position, actuating means supported by the body, and means operated by said actuating means for moving the switching member to on and off positions on successive movements of the actuating means.

In testimony whereof I affix my signature in presence of two witnesses.

JOSEPH SACHS.
